Primary Examiner — Tamara L Hahn(74) *Attorney, Agent, or Firm* — Knobbe, Martens, Olson & Bear, LLP(57) **CLAIM**

The ornamental design for a pallet, as shown and described.

DESCRIPTION

FIG. 1 is an elevational front view of the pallet, showing our new design;

FIG. 2 is an elevational side view thereof;

FIG. 3 is a top view thereof;

FIG. 4 is a bottom view thereof;

FIG. 5 is a top, front perspective view thereof;

FIG. 6 is a bottom, front, perspective view thereof; and,

FIG. 7 is an enlarged partial front view thereof.

The broken lines in the drawings depict portions of the pallet that form no part of the claimed design. The dot-dash broken lines shown in FIG. 7 are for notating a partial view that form no part of the claimed design.
